UNITED STATES PATENT OFFICE.

SAMUEL W. LUDLOW, OF MADISONVILLE, OHIO.

FIRE-ALARM AND TELEPHONE SYSTEM.

SPECIFICATION forming part of Letters Patent No. 450,466, dated April 14, 1891.

Application filed October 25, 1890. Serial No. 369,306. (No model.)

To all whom it may concern:

Be it known that I, SAMUEL W. LUDLOW, a citizen of the United States, residing at Madisonville, in the county of Hamilton and State 5 of Ohio, have invented certain new and useful Improvements in Fire-Alarm and Telephone Systems, of which the following is a full, clear, and exact description, reference being had to the accompanying drawings, 10 forming part of this specification.

My improvements relate to a combination of fire-alarm and telephone system whereby an alarm of fire may be automatically communicated to the telephone exchange without 15 in any way altering said telephone system or affecting the ordinary telephonic intercommunication between the telephone exchange or station and the subscribers and users.

My invention is intended to utilize the ordinary telephone systems in use throughout the country by automatically looping onto the telephone-line wire upon an outbreak of fire a magneto-electric generator with mechanism to operate the same and system of 20 switches and circuits mechanically and automatically operated in connection with the subscriber's telephonic transmitter, so that upon a fire occurring the train of mechanism may be set in action, a call sent to the exchange in the usual way, the subscriber's telephonic transmitter switched into the circuit, and a signal agreed upon, such as the ringing 25 of a bell, conveyed audibly to the operator at the exchange. I accomplish this result by new and improved construction and arrangement of parts, which will hereinafter be more particularly pointed out and claimed.

Any of the well-known forms of thermostats or devices for determining the presence 30 of fire may be used without departing from the spirit of my invention, which in the main consists of mechanism to be set in operation by the action of heat, whereby through suitable switches and electrical circuits the subscriber's telephonic instruments are operated 35 automatically, just as a subscriber would operate them if personally present, except that instead of the human voice announcing an alarm of fire that announcement is made by 40 the ringing of a bell or some other agreed-upon signal. When my mechanism is not in operation, the ordinary use of the telephone-

instruments is not affected in any way, nor are any supplemental wires needed to connect the house to be protected from fire with the 55 telephone exchange, nor any changes or modifications of any kind needed at the exchange.

In the drawings, Figure 1 is a front view of the box containing my device with the lid opened and the mechanism in place for sending the call to the exchange and switching the various currents. Fig. 2 is the same view with the box and parts of the magneto electric generator in section. Fig. 3 is a cross-section taken on lines $x-x$ of Fig. 1, looking in the direction of the arrow. Fig. 4 is a side view of the apparatus, the side of the box being removed. Fig. 5 is a diagram of various circuits. Fig. 6 is a perspective view showing the spring-connections, the working 70 parts of the apparatus being removed. Fig. 7 is a horizontal cross-section of the portion of the box shown in Fig. 6.

A is a suitable box to hold the working parts with a hinged door or lid B. At the top and 75 bottom of this box are the binding-posts a, b, c, d, e, f, g, and h, from which posts the various external connections are made. From post a connection is made with the telephone line-wire and from post b to the telephone apparatus, so that when posts a and b are in electrical connection within the box the circuit is from the exchange into the box at post a and out again at post b and to the subscriber's telephone, and this is the normal condition 80 when the fire-alarm apparatus is not in operation. From posts c and d connection is made by separate wires to the opposite ends of the primary coil of the microphone, and from posts e and g by separate wires to the 85 opposite ends of the microphone induction-coil of the telephone apparatus of the subscriber, so that when posts c and d are in electrical connection within the box and electrical connection is made within the box between posts a and e and between posts b and g a circuit will be established through the primary coil of the transmitter with the microphone-battery, and another circuit will be established from the exchange through post 90 a to post e, to secondary coil of transmitter, to post g, to post b, and to the telephone-instruments. From posts f and h connection is 95 made to the thermostats a'' and thermostat-

battery b'' , as shown in diagram, Fig. 5, by wires c'' and d'' , so that when the circuit is completed through the thermostat by the action of heat the train of mechanism within the box may be set in operation to make the various connections and to set in action the bell or other signal, the sound of which is to be conveyed to the exchange.

C C are a pair of horseshoe-magnets, and D the armature of same, the armature and its shaft E being driven by the gear-wheel F on shaft G, which meshes with the pinion II on the armature-shaft. The armature D is incased in the usual metallic box K, which is supported on legs i to the bottom of the case, the armature-shaft being journaled in this box K. On top of the box K the standards L L and collars M M are secured, and in these collars the shaft G is journaled. The shaft G is operated by a coiled spring N, a ratchet-wheel k, and dog l, holding the spring when wound up, while the wheel O, rigidly attached to the shaft with dog m, engaging a tooth therein, prevents the shaft G from revolving until the dog m is released, as hereinafter described. The spring is wound up by a suitable key fitting over the end of the shaft G, which extends without the box.

Between the collars M M, on which the shaft G is journaled, is a screw-threaded collar P, keyed thereto so as to revolve with the same. Upon this collar P a threaded nut or collar R rides, which is prevented from revolving with the collar P by a pin n, which slides in a slot p in the cross-bar o between the standards L L. It will be manifest from this arrangement that as the shaft G revolves the nut R will have a positive movement from one end of the collar P to the other. Loosely turning on shaft G is the arm S, carrying at its upper end a weighted ball r. This arm and ball are held up by the armatures of the electro-magnet T, the arm being slightly out of the perpendicular, so as to rest against the end of the armature. The arm is prevented from falling in the other direction by the stop t. The wheel O, having one notch u therein, is rigidly attached to shaft G, and within this notch u the dog m catches to hold same from being revolved by the action of the spring N; but when a current is passed through the coil of electro-magnet T the armature will be attracted, release the arm S, and allow the ball r to fall, and the lower end of the arm S will strike the projection v on dog m and release the wheel O, thus allowing the shaft G to revolve under the action of spring N. After the arm S and ball r have fallen far enough to release the dog m they are caught on the support U and prevented from rebounding by the catch w. Upon the outside of the box is an electric bell, as shown by the dotted lines in Fig. 1. One end of the coil of this bell is connected by metallic strips with the spring a' by wire 12 and the other end with spring b' by wire 13. The location of this electric bell is not material, so long as it is in the neighbor-

hood of the subscriber's telephone, so that its ringing may be heard at the exchange, and it is shown here on the outside of the box holding the other parts of the apparatus merely for convenience. The best position for this bell would probably be immediately above or alongside of the subscriber's transmitter, but so as not to interfere with the ordinary use of the telephone. The thermostat-wires from the posts f and h are electrically connected by wires 9 and 10 with the springs c' c', secured to the back of the box, which extends out in front of the springs a' b' and at right angles to said springs, these springs c' c' being connected together by hard rubber or other non-conductor. The electro-magnet coil is in electric connection with the springs d' d', secured to the side of the box with their ends bent at right angles, so as to come in contact with the thermostat-springs c' c' when the device is not in operation. In this way the thermostat is always in connection with the electro-magnet T. As soon, however, as the circuit is completed through the thermostat by the action of heat the armature s of the magnet is attracted, which allows the ball r to drop, and the lower end of the arm S, coming in contact with the dog m, drives it back against the springs c' c', which breaks the connection between the thermostat-wires and the electro-magnet T and makes connection between the thermostat-springs and the bell-springs, and as long as the circuit is complete through the thermostat the bell will continue to ring. Three springs e', f', and g', separate from each other, are located at the side of the box, the center one f' being in connection with the metallic support U when the ball r is up, and one of the others, as g', having a bridge h' coming out in front of the other e'. When the ball r has fallen, the knobs shown thereon in the drawings being insulating material, the connection between spring f' and support U is broken, and by means of the bridge h' the three springs are brought into electrical connection. The wire from the exchange to post a is in electrical connection by suitable metallic strips in Fig. 5, wire 1, with the spring f', and the wire to the telephone from post b is connected by wire 2 with support U, so that while the ball r is up the circuit from the exchange to the telephone is into the box at post a, to spring f', to U, to post b, and to telephone. The springs e' and g' are in electrical connection by wires 3 and 4 with posts c and d, which are in connection with the primary coil of the subscriber's microphone, so that when the ball r is down a circuit will be established with subscriber's microphone-battery, while the circuit from spring f' to support U will be broken.

The coil of the armature D of the generator is in connection at one end with the metallic box K and at the other with insulated point k', which point is in connection by spring l' with support U and wire 2. On the metallic nut R are the pins m' m', and when the nut

R is at one end of the collar P the spring n' is in connection therewith, the spring n' is insulated from the box K, and the nut itself is in electrical connection with box K. Looped 5 into wire 1 is the wire 5, through which connection is made with spring n' , and in this way as soon as the direct connection is broken between wires 1 and 2 by the fall of the ball r a circuit is made from the exchange through wires 1 and 5, spring n' , nut R, box K, armature-coil, spring l' , support U, and wire 2 to the telephone, and thus the revolution of the armature D will generate a current which 10 will drop the subscriber's annunciator-button 15 at the exchange. After a certain number of revolutions, however, the nut R will be carried so far over as to break the connections between it and the springs n' and o' , and further revolutions of the armature D will have 20 no effect on the transfer of sound over the telephone-wires. Directly opposite to the springs n' o' on the other side of the nut R are the springs r' r' , one of which is in connection by wire 6 with post e and the other 25 by wire 8 with wire 2, and as soon as the nut has traveled far enough to break connection between the pins m' m' and spring n' the springs r' r' come in contact with said pins m' m' . Another spring p' , in connection with 30 binding-post g by wire 7, is arranged so that when connection is broken between n' and the nut R the spring p' will come into connection with n' . Therefore as soon as the nut R has traveled from one end of the collar P to the 35 other a complete circuit will be established from the exchange through wires 1 and 5, spring n' , spring p' , post g to the secondary coil of subscriber's microphone, back to post e , wire 6, one spring r' , nut R, other spring r' , 40 wire 8, wire 2 to telephone, and thence to ground, as all the circuits to the telephone will be when the instruments are not in use.

The operation of my device will, I take it, be manifest from the above description. Having 45 established throughout the building to be protected from fire the desired number of thermostats, arranged in connection with a battery to establish a circuit when a sufficient degree of heat has been reached, the 50 proper wire-connections can then be made with the binding-posts on subscriber's telephone, as above described, the coiled spring N being wound up, the ball r raised and held up by armature s , and the device is ready to 55 send in an alarm of fire. The subscriber's telephone can be used without being affected in any way, the circuit being complete from the exchange to the telephone through spring f' and support U. As soon, however, as a 60 current is established through the thermostat the ball r will be released, the dog m will be released from the wheel O, allowing the shaft G, and with it armature D, to revolve, a call will be sent to the exchange, the nut R 65 will travel on the collar P, connection will be made with the microphone, and the thermostat will ring continuously the electric bell

placed in the neighborhood of the microphone, and the sound will be conveyed through the transmitter to the exchange.

I have shown in my device an electro-magnet to drop the ball which sets in operation the mechanism shown, and also an electric bell to make the signal of fire; but it is obvious that the ball may be dropped or the 70 dog which holds the mechanism released by any well-known mechanical means, and that any of the well-known mechanical devices for determining the presence of heat may be employed for that purpose, and that it is not 75 necessary that a bell should be used, but a whistle or rattle or other instrument to make a continuous noise could be adopted.

I am aware that it has been proposed hitherto to connect the telephone exchange with 80 fire-alarm apparatus; but all arrangements hitherto devised either require the employment of a separate system of wires to the exchange or require modification to be made at the telephone exchange which would necessitate changes in the ordinary telephone system; while my device is distinguishable from 85 all earlier devices of a like nature, in that no change whatever is required in the telephone system as ordinarily used, nor does the connection of my fire-alarm apparatus with the telephone in any way affect the ordinary use 90 of the telephone.

Having thus fully described my invention, what I claim, and desire to secure by Letters 95 Patent, is—

1. In a combined fire-alarm and telephone system, the combination, with the telephone-line wire and telephone apparatus and electrical means for sending a call to the exchange 105 independent of the telephone-instruments, of electrical circuits from the primary and secondary coils of the subscriber's transmitter independent of the ordinary telephone-circuits of the telephone apparatus, switches to 110 close said circuits, and means for operating them automatically after a call has been sent, so that the telephone-transmitter may be placed in circuit independent of the telephone-circuits of the ordinary telephone apparatus 115 to convey a sound to the exchange, substantially as shown and described.

2. In a combined fire-alarm and telephone system, a telephone-line wire, an independent magneto-electric generator in connection 120 therewith, and circuits and switches in connection therewith for throwing the subscriber's telephone-transmitter in circuit independent of the ordinary transmitter-circuits with mechanism for operating said generator and 125 switches, in combination with fire-alarm apparatus and means for setting said mechanism in operation upon the outbreak of fire, and an electric bell in connection with the fire-alarm apparatus, substantially as shown 130 and described.

3. In a fire-alarm and telephone apparatus, the combination of thermostat and battery, electro-magnet and electric bell, wires in con-

nection therewith so arranged that the open terminals of the thermostat-circuit swing between the open terminals of the electro-magnet coil and the electric-bell coil, said thermostat-terminals being in connection with the electro-magnet until the circuit is completed through the thermostat, when their connection is automatically broken and made with the electric bell, substantially as shown and described.

4. In a fire-alarm and telephone apparatus, the combination, with thermostat and battery, of an electro-magnet T, armature s, the weighted arm S, held up thereby, and an electric bell with springs a' b', c' c', and d' d', with the circuits described, so that the passage of an electric current through the electro-magnet will release the arm S and allow it to switch the thermostat-current from the electro-magnet to the bell, substantially as shown and described.

5. In a fire-alarm and telephone apparatus, the combination, with the telephone-line wire, of wires 1 and 2, forming a loop therewith, wire 5, connecting said wires 1 and 2 through the armature-coil of a magneto-electric generator, shaft to operate same, and weighted arm S, released by the action of heat, which on falling breaks connection between wires 1 and 2 and allows a circuit to be established with the exchange through the said generator, substantially as shown and described.

6. In a fire-alarm and telephone apparatus, the combination of the shaft G, threaded collar thereon with nut arranged to have a

positive movement along said shaft, with spring n' in electric connection with wire 1, spring p' in electric connection with the transmitter induction-coil, and springs r' r', one in connection with transmitter induction-coil and the other with wire 2, said springs arranged, as described, so that as the nut moves with the revolution of the shaft the generator armature may be thrown out of circuit and a complete circuit made with the exchange 45 through the induction-coil of subscriber's transmitter, substantially as shown and described.

7. In a fire-alarm and telephone apparatus, the combination of magneto-electric generator with shaft to operate same driven by a spring, wheel O, and dog m, holding same, weighted arm S, dropped by the action of fire and arranged to release said dog and allow the shaft to operate springs e' g' in connection with the primary coil of subscriber's transmitter and brought in contact by the falling of arm S, nut R, moving with the revolutions of shaft G and in connection with the armature-coil of the generator, and springs 55 n' p' r' r' with electric connections, as described, so that upon the dropping of the arm S a call will be sent to the exchange and thereupon the subscriber's telephone-transmitter automatically thrown into the circuit, substantially as shown and described.
